MACHINE FOR PLACING ARTICLES OF FLAT OR OBLONG CROSS
SECTION SIDE-BY-SIDE IN AN OBLIQUE POSITION

Filed Jan. 30, 1931

Fig.4

Fig.1

Fig.3

This cross-sectional diagram illustrates a mechanical assembly, likely a bearing housing or a similar component. The assembly is shown in a vertical orientation. Key features include a central shaft or pin (4) supported by bearings (5) within a housing (6). A lock washer (15) is positioned on the shaft. A flange (2) is attached to the top of the housing. A retaining ring (51) secures a bearing (52) to the housing. A shoulder (16) is visible on the shaft. The bottom of the housing is supported by a base (49). A label (38) points to a hatched area at the very bottom, which represents the ground or a foundation.

MACHINE FOR PLACING ARTICLES OF FLAT
OR OBLONG CROSS SECTION SIDE-BY-
SIDE IN AN OBLIQUE POSITIONJohannes Neff, Dresden, Germany, assignor to
Universelle Cigarettenmaschinen-Fabrik J. C.
Mulier & Co., Dresden, GermanyApplication January 30, 1931, Serial No. 512,381,
and in Germany February 4, 1930

9 Claims. (Cl. 226—5)

My invention relates to machines for placing articles of flat or oblong cross section, such as cigarettes, side by side in an oblique position.

It is an object of my invention to so design 5 a machine of this type that the articles automatically assume the oblique position desired.

To this end I provide a downwardly extending chute with a curved bottom for the reception of the articles.

10 The articles supplied at the upper or inlet end of the chute and speeded up at this point engage from below and erect into oblique position the articles which are already in the chute and are temporarily arrested. The oblique position of the articles is due to the curvature of 15 the bottom of the chute. The articles assume a position with respect to each other which is similar to that of scales or tiles. The articles are subdivided into groups and when the articles 20 which make up a group have been placed in oblique position the means for arresting them is retracted and the group is fed toward a packing station where the articles are delivered to a package.

25 A machine for handling cigarettes in the manner described will be shown by way of example but it is understood that my invention may be applied to any other articles of flat or oblong cross section.

30 It has already been suggested to form groups of cigarettes in which the cigarettes are placed as described but in the old machines for effecting this it was necessary to supply the cigarettes separately, or to provide mechanism for erecting 35 them.

In my machine the cigarettes are influenced by gravity and velocity only and the required overlapping position is thus obtained without mechanical means, damage to the cigarettes is prevented and the output is necessarily high as the 40 cigarettes require speeding up at the inlet end of the chute.

The cigarettes are fed to my machine in the usual manner by conveying cylinders or conveying chains but are sped up at the inlet end 45 of the chute, preferably by rotary brushes.

In a preferred embodiment of my machine, in combination with the rotary brushes referred to, and a stop for arresting the first cigarette in 50 each group, that is, the cigarette which leads in the feeding direction, I provide a pusher for positively moving the last cigarette of each group into position to be engaged by an auxiliary feeder which moves the group to an intermediate station 55 ahead of the packing station, and a retainer

which engages behind the last cigarette of the group and holds the group at the intermediate station until it is moved on to the packing station and delivered to a package.

The operations of the various means are so timed with respect to each other that the stop for the first cigarette remains in active position during the operation of the pusher but is retracted as soon as the auxiliary feeder starts to operate, and the retainer is moved to engage 60 behind the last cigarette when the group has arrived at the intermediate station.

In the drawing affixed to this specification and forming part thereof a machine embodying my invention is illustrated diagrammatically by way 70 of example.

In the drawing

Fig. 1 is a partly sectional elevation of my machine.

Figs. 2 and 3 are sections on the lines 2—2 and 75 3—3 in Fig. 1, respectively, and

Fig. 4 is a detail showing part of the curved chute and its stop.

Referring now to the drawing, 38 is the base plate of the machine, and 34 is its driving shaft 80 which is mounted to rotate in bearings 39 and 40, Fig. 2. 7 is a sprocket keyed on the shaft 34 and 1 is a chain-conveyer for feeding cigarettes to the machine which is operated by the sprocket 7. Two links of the chain 1 only are shown in Fig. 85 1, each with a pair of recesses 41 for the reception of cigarettes. 35 is a spur gear on one end of the shaft 34 which through intermediate gears 33 and 42 rotates a spur gear 32 on the outer end of a shaft 43 in a bearing 44. 3 is a speeding-up brush on the inner end of the shaft 43. 45 is a shaft in a bearing 46 which is on the opposite side of the machine and in line with the shaft 43, and 47 is another speeding-up brush on the inner end of shaft 45. Means, not shown, is provided for rotating the brush 37 at the same speed as the brush 3. 48 is the shaft of the auxiliary feeder 30 which is mounted above and slightly to the rear of the brush shafts 43 and 45, 37 is a spur gear on the shaft 48, and 36 is an intermediate gear in mesh with gears 32 and 37.

The cigarettes which are fed to the machine by the chain 1 in the direction of the arrow, are delivered by the links to two tracks 2 on which their ends are supported, and moved as far as 105 "x". Here they are engaged by the brushes 3 and 47 and delivered to a chute the front end of which has a curved bottom as shown at 4. 6 are guiding strips extending in parallel relation to and above the rails 2 for holding the cigarettes 110

down on the chute 4. The cigarettes of each group are speeded up by the brushes. 5 is a stop which extends into the chute through a slot in its bottom, the stop being divided as 5 shown in Fig. 3, so as to engage the ends of the cigarettes near the rails 2 and the strips 6. The stop, or rather, the stops, 5 are secured to a rocking frame 15 which is pivoted at 49 to one arm of a rocking lever 16 fulcrumed at 17. 50 10 is a spring which tends to pull the frame 15 to the rear, 51 is a transverse bar in the frame 15, and 52 is a check on the frame of the machine to which the bar 51 is applied by the spring 50. 13 15 is a roller at the free end of the rocking lever 16 and 19 is a cam on a shaft 53 to which the roller 18 is applied by a spring 54. Rotation is imparted to the shaft 53 by any suitable means, not shown.

20 8 are pushers which are fitted to slide in radial slots of the sprocket 7, each with a finger 8' at one end, and a roller 9 at the other, and 11 are springs tending to apply the rollers 9 to fixed cams 10.

25 The pusher fingers engage the cigarettes as soon as they have been delivered to the tracks 2 by the links 1, and move them toward the brushes 3, 47. The rollers 9 at the ends of the pushers 8 the fingers 8' of which have rotated so far, now rise on the cams 10 and advance into 30 slots of the chute 4, placing the last cigarette of the group in the desired oblique position under the action of the curved bottom of the chute, and then drop from the cams under the action of 35 their springs 11. The cigarettes are now grouped in the position illustrated in Fig. 4 being in an oblique position on the curved bottom of the chute 4, and overlapping each other like scales or tiles.

40 The last cigarette of the group after having been released by the pusher fingers 8' is ready to be engaged by one of the arms of the spider 30. The spider, or auxiliary feeder, 30 is equipped with fingers 12 at the ends of its arms which are pivoted to the arms at 30' and equipped with 45 springs 31 tending to hold the fingers in line with the arms. When the auxiliary feeder 30 engages the last cigarette of a group by one of its fingers 12 the stops 5 are retracted through the 50 medium of the cam 19 and the parts connected to it and the finger 12 now push the group of cigarettes into a horizontal passage 14 adjoining the chute 4. When the first cigarette of the group has arrived at the intermediate station y the finger 12 strikes a dog 29 which is so pitched 55 with respect to the position y that the last cigarette of the group is just below it when the first one is at y . The feeder 30 rotates continuously and the fingers 12 slide across the dog 29 while 60 tension is put on their springs. 26 is a spur gear on the shaft 53, 27 is an intermediate gear, and 28 is a gear on a shaft 55 which meshes with gear 27. 25 is a cam on the shaft 55, and 22 is a double-armed rocking lever which is fulcrumed at 56, with one of its arms engaging the cam 25 65 under the pressure of a spring 24. 23 is a link pivoted to the other arm of the lever at one end, and to a retainer 20 at the other. The retainer 20 is fulcrumed on the passage 14 at 21 and its 70 operation by the lever 22 is so timed with respect to the operation of the stop 5 and the arms of the auxiliary feeder 30 that the stop is retracted, whereupon one of the fingers 12 pushes the group toward the intermediate station where the first cigarette is at y , and the retainer 20 engages 75 behind the last cigarette. It is particularly im-

portant that the fingers 8' of the pushers 8 not only place the last cigarette in the oblique position required on the curved bottom of the chute 4 but also move it into a definite position in the chute where it is engaged by one of the fingers 12. The ratio of the gears intermediate the 80 shafts 34 and 48 is such that the pusher fingers 8' release the last cigarette shortly before it is engaged by one of the fingers 12.

I wish it to be understood that I do not desire to be limited to the exact details of construction shown and described for obvious modifications will occur to a person skilled in the art.

90 In the claims affixed to this specification no selection of any particular modification of the invention is intended to the exclusion of other modifications thereof and the right to subsequently make claim to any modification not covered by these claims is expressly reserved.

I claim:

1. In a machine for placing articles of flat or oblong cross section side by side in an oblique position, a downwardly extending chute having a curved bottom, means for feeding articles to said chute, a stop for temporarily arresting the articles in said chute, and means for intermittently moving said stop into, and retracting it from, 100 said chute.

105 2. In a machine for placing articles of flat or oblong cross section side by side in an oblique position, a downwardly extending chute having a curved bottom, means for feeding articles to said chute, a stop for temporarily arresting the articles in said chute, means for intermittently moving said stop into, and retracting it from, 110 said chute, and means near the inlet end of said chute for speeding up said articles.

115 3. In a machine for placing articles of flat or oblong cross section side by side in an oblique position, a downwardly extending chute having a curved bottom, means for feeding articles to said chute, a stop for temporarily arresting the articles in said chute, means for intermittently moving said stop into, and retracting it from, 120 said chute, and a rotary brush near the inlet of said chute for speeding up said articles.

125 4. In a machine for placing articles of flat or oblong cross section side by side in an oblique position, a downwardly extending chute having a curved bottom, means for feeding articles to said chute, a stop for temporarily arresting the articles in said chute, means for intermittently moving said stop into, and retracting it from, 130 said chute, and an auxiliary feeder for moving said articles to an intermediate station ahead of a packing station.

135 5. In a machine for placing articles of flat or oblong cross section side by side in an oblique position, a downwardly extending chute having a curved bottom, means for feeding articles to said chute, a stop for temporarily arresting the articles in said chute, means for intermittently moving said stop into, and retracting it from, 140 said chute, and an auxiliary feeder including an article-engaging finger and resilient means holding said finger in a definite position; for moving said articles to an intermediate station ahead of a packing station.

145 6. In a machine for placing articles of flat or oblong cross section side by side in an oblique position, a downwardly extending chute having a curved bottom, means for feeding articles to said chute, and an auxiliary feeder including an article-engaging finger and resilient means hold-

ing said finger in a definite position; for moving said articles to an intermediate station ahead of a packing station, and means on said chute for moving said finger out of active position with respect to said articles.

7. In a machine for placing articles of flat or oblong cross section side by side in an oblique position, a downwardly extending chute having a curved bottom, means for feeding articles to said chute, a stop for temporarily arresting the articles in said chute, means for intermittently moving said stop into, and retracting it from, said chute, an auxiliary feeder for moving said articles to an intermediate station ahead of a packing station, and means for retaining them at said intermediate station.

8. In a machine for placing articles of flat or oblong cross section side by side in an oblique position, a downwardly extending chute having a

20

curved bottom, means for feeding articles to said chute, a stop in said chute for temporarily arresting said articles, an auxiliary feeder for moving said articles to an intermediate station ahead of a packing station, and means operatively connected to said stop for retaining them at said intermediate station.

9. In a machine for placing articles of flat or oblong cross section side by side in an oblique position, a downwardly extending chute having a curved bottom, means for feeding articles to said chute, a stop for temporarily arresting the articles in said chute, means for intermittently moving said stop into, and retracting it from, said chute, and an auxiliary feeder adapted to move in time with said stop for moving said articles to an intermediate station ahead of a packing station.
